UNITED STATES PATENT OFFICE.

JOSEPH SYLVAN, OF CHICAGO, ILLINOIS.

RIDGE-VENTILATOR CONSTRUCTION.

1,410,625.

Specification of Letters Patent. Patented Mar. 28, 1922.

Application filed December 17, 1920. Serial No. 431,410.

To all whom it may concern:

Be it known that I, JOSEPH SYLVAN, a citizen of the United States, and a resident of Chicago, in the county of Cook and State of Illinois, have invented certain new and useful Improvements in Ridge-Ventilator Constructions; and I do hereby declare that the following is a full, clear, and exact description thereof, reference being had to the accompanying drawings, and to the letters of reference marked thereon, which form a part of this specification.

This invention relates to improvements in ridge ventilator construction, and consists of the matters hereinafter described and more particularly pointed out in the appended claims.

The object of the invention is to improve the construction and operation of that type of ventilator illustrated and described in my pending application for patent, Serial No. 377,474, filed April 29, 1920.

The many advantages of the invention will more fully appear as I proceed with my specification.

In the drawings:-

Figure 1 is a transverse section through the top part of a skylight to which my improved ridge ventilator construction has been applied.

Figure 2 is a horizontal section through the same on the line 2-2 of Figure 1.

Figure 3 is a vertical detail sectional view on enlarged scale taken on the line 3-3 of Figure 1.

Figure 4 is another vertical detail sectional view taken on the line 4-4 of Figure 1.

Figure 5 is a view similar to Figure 1 but with the parts in a changed relation.

Figure 6 is a horizontal section through the same taken on the line 6-6 of Figure 5.

Figure 7 is an enlarged detail view of the parts shown in the middle of Figure 6.

Figure 8 is a perspective view of a bracket embodied in my improved construction and which will be more specifically referred to later.

Figure 9 is a view in elevation of one arcuate rack bar embodied in my improved construction.

Figure 10 is a view in elevation of another arcuate rack bar embodied in my improved construction.

Figure 11 is a view on an enlarged scale of parts shown in the top end of Figure 1.

Figure 12 is a view showing a modified form of the parts shown in Figure 11.

Referring now in detail to that embodiment of the invention illustrated in Figures 1 to 11 inclusive of the accompanying drawings:-15 indicates the downwardly and outwardly inclined rafters of a skylight, the outer ends of which are connected to a horizontal cross beam 16. Arising from the middle of the cross beams 16 are standards 17 to which the abutting inner or top ends of the rafters are also secured, the top end of said standards extending upwardly beyond said abutting ends of the rafters.

The rafters 15 are connected by longitudinally extending angle bars 18 spaced an equal distance on each side of the standards 17 and to said angle bars are fixed the inner top ends of glazing bars 19 which support the skylight panels 20. It is apparent that an opening 21, is defined at the ridge of the skylight by the angle bars 18 and the top inner ends of the panels 20.

To the top end of each standard 17, embodied in the skylight, is secured an upright strap 22 which terminates in an eye or loop 23 to receive and support a short longitudinal stub shaft 24 arranged in the median line of the skylight.

25-26 indicate the ventilator sections or frames which are pivoted on the stub shafts 24 so as to be capable of a swinging movement thereon, away from and toward the angle bars 18, to open and close the skylight opening 21. Each ventilator section comprises inner top, and outer bottom, longitudinal angle bars 27-28 which are connected together by glazing bars 29 providing the support for the usual panels 30 of said sections. Secured to the inner top angle bars 27 of both sections, are straps 31, which include eyes 32 that engage the ends of the stub shafts 24, one on each side of the strap eye 23. Pins 33 extending through the ends of said shafts lock the straps 31 against endwise movement on the said shaft. Fixed to the outer bottom angle bars 28 are inwardly extending gutter strips 34 which catch the water of condensation forming on the inner surface of the sections or frames 25 and 26.

35 indicates a one piece ridge strip which bridges and closes the space or gap between the inner top ends of the sections 25-26. In the present instance said ridge strip is made of sheet metal and includes a trans-

versely curved top wall 36, and side walls 37 extending parallel with, but spaced from the adjacent flanges of the associated angle bars 27, as shown in Figures 1 and 11. The side 5 walls of the ridge strip are formed to provide longitudinally extending grooves 38 and in each groove is placed an elastic, waterproof material 39 which extends over upon the angle bars 27 as shown in Figure 10. The top marginal ends of the panels 30 extend into the grooves 38 of the ridge strip and engage upon the elastic material 39, the edges of said panels having semi-cylindric metallic protecting strips 40 arranged concentric with the grooves 38. The several 15 parts are so arranged and so located with respect to the axis of the stub shafts 24, that as the sections 25—26 are being swung from a closed to an open position or vice versa, 20 there will be a slight raising and lowering movement of the ridge strip, equal to the length of the arc about which the inner ends of the panels 30 travel, about the shaft as an axis, due to the engagement of the inner 25 ends of the panels in the grooves 38.

The means for operating the sections are as follows:—42—43 indicate arcuate rack bars—one associated with each swinging section. Each rack bar is concentric with the 30 shafts 24 and the rack bar 42 is connected at one end to a clip 42^a on the section 25, while the rack bar 43 is connected at the opposite end, to a similar clip 43^a on the section 26. Said clips 42^a—43^a are secured to the outer 35 angle bars 28 in both instances. When both sections 25—26 are in their normally closed position, as shown in Figures 1 and 2, said rack bars extend in a plane substantially at right angles to the longitudinal median line 40 of the skylight.

The rack bar 42 has teeth 42^b, which extend from the free (right hand) end thereof, to almost the middle of said bar where a notch 44 is provided, the purpose of which 45 will appear later. The rack bar 43 has teeth 43^b, which extend from the free (left hand) end of the rack bar to a point beyond the middle thereof as shown in Figure 10, which point is in line with that tooth 42^a of 50 the rack 42 nearest the notch 44. On the front face of the bar 42 is an under cut block or cleat 45, and on the opposite side of said bar at the free (right hand) end thereof is a hook 46. On the rear face of the rack bar 55 43 at its middle is a block or cleat 47, having a beveled end adapted to coact with the under cut block or cleat 45 before mentioned. On the front surface of the free (left hand) end of said bar 43, which is beveled as 60 shown at 48, is secured a flat leaf spring 49 having a hooked end.

The teeth of said rack bars are adapted to mesh with a gear pinion 50, fixed on a longitudinal shaft 51 extending through the uprights or standards 17. Preferably I secure

to said standards, bearing boxes 52 for said shaft, and to one face of said boxes are secured bracket yokes or plates 53 (see Figures 4 and 8) which straddle the rack bars and prevent them from jumping out of mesh 70 with the gear pinion. On the front and rear parts of said plates are provided, oppositely facing, stop hooks 54—55, which are adapted to be engaged by the hook 46 on the rack bar 42 and the hook spring 49 on the 75 rack bar 43 respectively. Secured to shaft 51, is a grooved pulley 56, over which is trained an actuating chain 57, which hangs down in the usual loop, in a position within convenient reach for the person who is to 80 operate the same.

In Figure 12, I have shown a modified form of ridge strip construction wherein a flexible waterproof covering strip 60 encloses the ridge strip 35, the margins of the 85 strip 60 engaging in the grooves 38 of said ridge strip and there being secured to the angle bars 27. In this construction the elastic material 39 is interposed between the margins of the covering strip and the inner 90 top marginal end parts of the panels. The covering strip 60, being flexible, will readily accommodate itself to such slight movement as is necessary in the raising and lowering of the ridge strip, during the swinging 95 movement of said sections 25—26.

When the ventilator sections 25—26 are in their normally closed position, as shown in Figure 1, the beveled block or cleat 47 on the rack bar 43 is engaged with the under 100 cut block or cleat 45 on the bar 42 so that said sections are connected together there-through, and counter balance each other. Thus, the outer angle bar 28 of both sections 25—26 are normally spaced above, but overhang the angle bars 18 of the skylight, as 105 shown in Figure 1. By reason of the termination of the teeth 42^b—43^b as before mentioned, the teeth 42^b of the rack 42 will be out of mesh with the gear 50 while the teeth 110 43^b of the rack bar 43 will be in mesh with said gear.

Assume that it is desired to open the section 26. A pull on the right hand lap of the chain 57 will rotate the shaft 51 and the gears 50 thereon (when the skylight is of such length requiring more than one set of rack bars 42—43) which will cause said rack bar 43 to move to the right and swing the section into its open position. If it is 120 desired to open said section only a part way, the pull on the chain 57, is discontinued when the desired position is reached, after which the friction of the shaft 51 in its bearings will be sufficient to overcome the gravity action of said section, and thus hold it in the part way open position. As soon as the block 47 moves away from the block 45, the counter balancing action between the sections is destroyed and the section 25 will 125 130

descend by gravity until its angle bar 28 engages upon the associated angle bar 18 of the skylight and will remain in this position until the block or cleat 45 is again engaged by the block or cleat 47 of the rack bar 43, as will later be described. It is apparent that the notch 44 in the bar 42 prevents engagement with the gear 50 in this slight movement of the said section.

10 As the pull on the right hand lap of the chain 57 is continued, the said section 26 will continue to swing toward its full open position, wherein it will extend into a position slightly inclined upwardly from the horizontal plane of the stub shafts 24. Thus when a wind is blowing over the top surface of the section 26, a partial vacuum is produced beneath its outer margin which will act to establish an up draft through the ventilator opening 21. As this full open position is approached, the spring 49 on the rack bar 43 will engage against the hook 55 on the bracket 53, said spring then acting to swing the beveled free end 48 of said rack bar 43 toward the rack bar 42, which beveled end is in a position to pass the adjacent end of the under cut block or cleat 45, on the rack bar 42 as shown in Figure 7. When the pull is discontinued, the friction of the shaft 51 in its bearing will be sufficient to prevent the closing of the said section under its own weight. As is apparent from Figure 6, when the ventilator section is in its full open position, the free end of the rack 42 is flexed rearwardly, by reason of the engagement of the block 47 on the rack bar 43, thus putting the rack bar 42 under a flexure stress for a purpose to appear later.

When it is desired to swing both sections 40 25-26 in their open position, as shown in dotted lines in Figure 1, this is accomplished as follows:—The section 26 is first swung into its full open position as just above described. This brings the beveled end 48, of the rack bar 43, into a position ready to engage the undercut block or cleat 45 on the rack 42. The left hand lap of the chain is then pulled downwardly, which will rotate the gear in a counter clockwise direction. This will cause the rack bar 43 which is still in mesh with said gear to move toward the left, when the beveled end 48 of the rack bar 43 will engage the under cut block 45 on the rack bar 42 and impart a 50 similar movement to said rack bar 42. As the rack bar 42 thus moves, the tooth 42^b adjacent the notch 44 is brought into mesh with the gear 50 so that thereafter both racks are positively in mesh with, and are 55 actuated together as one, by said gear 50. The pull on the left hand lap of the chain being continued, the section 25 will swing upwardly and the section 26 will swing downwardly until both sections are in the 60 positions shown in dotted lines in Figure 1.

When both sections are open, they will extend at an angle, downwardly and outwardly inclined from the shafts 24, when the wind may blow in beneath the angle bar 28 of one section, across, but above the opening 21 in the skylight and then out beneath the angle bar 29 of the other section. 70

Should it be desired to swing the section 25 into open position, a further pull on the left hand lap of the chain 57 will cause the rack bar 42 to move toward the left, the rack bar 43 also moving to the left until its innermost tooth 43^b passes out of mesh with the gear 50 when said section 26 reaches its closed position, the section 25 continuing in 80 its swing towards its full open position until the hook 46 on the rear face of the free end of said rack bar 42 engages the hook 54 on the bracket clip 53, and stops the same, the section 25 then being in a position opposite that of the section 26 as shown in Figure 5. As the section swings toward its full open position, the free end of the rack bar 42 which is under a flexure stress as before described, will act to straighten out 85 by reason of its engagement with the rear wall of the bracket 53 and will then act through the block 47, to move the bar 42 toward the front wall of the bracket plate so that the beveled end of the said rack bar 43 95 is out of the plane of the undercut block on the bar 42. When it is desired to close the section 25, a pull is imparted to the right hand lap of the chain 57, which will swing the rack 42 to the right until the block 45 100 engages the block 47 when both sections are again closed and in their counter balancing position as shown in Figure 1.

With both sections in their closed position, and it is desired to open only the section 25, 105 the left hand lap of the chain 57 is pulled downwardly. The rack bar 43, being still in mesh with the gear 50, will act through the cleats 47-45 to impart a starting movement to the rack bar 42 to bring its first tooth 42^b into engagement with the gear 50 just as the last tooth at the middle of the rack bar 43 leaves the same, the slight movement of the associated section 26 being permitted by reason of the space normally existing between the angle bars 28 and 18 respectively when both sections are closed and counter balanced. A further pull on the left hand lap of the chain 57 will cause the rack bar 42 to move to the left, swinging the section 25 with it, until the hook 46 on the rack bar 42 engages the associated stop hook 54 on the bracket 53. When the section 25 is in its full open position, it will 110 extend in a plane, inclined upwardly from the horizontal, the opposite from that position of the section 26, shown in full lines in Figure 5. To again close the section 25, it is only necessary to pull on the right hand lap of the chain 57, the cleat 45 on the rack bar 115 120 125 130

42 again engaging the block 47 as it approaches the same so that both sections are again connected through the rack bars and will then counterbalance each other.

5 It is apparent, that the sections 25—26 may be opened and closed individually, and that to have both sections open simultaneously, the sections 26 must first be swung into a full open position to connect both sections together, after which a closing movement of the section 26 will impart an opening movement to the section 25.

10 It is apparent that the improved construction is strong and durable, is simple to operate, and is positive in its operation. The ridge construction is leak proof, and will not sag or warp.

15 While in describing my invention I have referred to certain details of mechanical construction and arrangement of parts, I do not wish to be limited thereto except as may be pointed out in the appended claims.

I claim as my invention:—

20 1. A ridge ventilator construction of the kind described, comprising in combination with means providing a ventilation opening, oppositely arranged angularly disposed ventilator sections normally closing said opening, said ventilator sections being pivoted at 25 their adjacent margins and being capable of a swinging movement away from and toward said ventilation opening, and an operating mechanism for swinging said sections into open and closed position, said operating mechanism including parts permitting either section to be swung individually or permitting both sections to be swung simultaneously, after one of said sections has been 30 swung into a fully opened position.

40 2. A ridge ventilator construction of the kind described, comprising in combination with means providing a ventilation opening, oppositely arranged angularly disposed ventilator sections normally closing said opening, said ventilator sections being pivoted at 45 their adjacent margins and being capable of a swinging movement away from and toward said ventilation opening, a bar connected to each section near its outer margin, an operating device capable of actuating either bar for swinging the associated section, said bars having coacting parts operable in the movement of one bar to connect both bars together, so that thereafter both 50 sections swing as one.

60 3. A ridge ventilator construction of the kind described, comprising in combination with means providing a ventilation opening, oppositely arranged angularly disposed ventilator sections normally closing said opening, said sections being pivoted at their adjacent margins and being capable of a swinging movement away from and toward said ventilation opening, an arcuate rack bar 65

connected to each section near its other margin, and an operating gear capable of being engaged by both rack bars, the rack bar associated with one section automatically engaging the rack bar associated with the other section, as the first section approaches 70 its full open position, so that thereafter both sections are connected together to swing as one.

4. A ridge ventilator construction of the kind described, comprising in combination 75 with means providing a ventilation opening, oppositely arranged angularly disposed ventilator sections normally closing said opening, said ventilator sections being pivoted at their adjacent margins and being capable 80 of a swinging movement away from and toward said ventilation opening, an arcuate rack bar connected to each section near its other margin, a manually operable shaft capable of rotation in either direction, and 85 a gear on the shaft, capable of being engaged by both rack bars, the rack bar associated with one section automatically engaging the rack bar associated with the other section, as the first section approaches 90 its full open position so that thereafter both sections are connected together to swing as one.

5. A ridge ventilator construction of the kind described, comprising in combination 95 with means providing a ventilation opening, oppositely arranged angularly disposed ventilator sections normally closing said opening, said sections being pivoted at their adjacent margins and being capable of a swing- 100 ing movement away from and toward said ventilation opening, an arcuate rack bar connected to each section near its other margin, an operating gear capable of being engaged by both rack bars, and a block on one 105 of said rack bars adapted to be engaged by the end of the other rack bar, as the section associated therewith approaches its full open position so that said rack bars are connected and may be actuated together in the opposite 110 direction.

6. A ridge ventilator construction of the kind described, comprising in combination with means providing a ventilation opening, oppositely arranged angularly disposed ventilator sections normally closing said opening, said sections being pivoted at their adjacent margins and being capable of a swing- 115 ing movement away from and toward said ventilation opening, an arcuate rack bar 120 connected to each section near its other margin, an operating gear capable of being engaged by both rack bars, a block on one of said rack bars, a spring on the end of the other rack bar adapted to shift said end of 125 said last mentioned rack bar into engagement with said block as said end approaches said gear, so that said rack bars are con-

nected and may be actuated together in the opposite direction.

7. A ridge ventilator construction of the kind described, comprising in combination 5 with means providing a ventilation opening, oppositely arranged angularly disposed ventilator sections normally closing said opening, said sections being pivoted at their adjacent margins and being capable of a swing- 10 ing movement away from and toward said ventilation opening, an arcuate bar connected to each section near its outer margin, each rack bar having teeth on its periphery, a gear adapted to be engaged by said teeth, 15 a bracket in which said gear is arranged and guiding said rack bars, the teeth on one of said rack bars terminating short of said gear and the teeth on the other rack bar terminating beyond said gear so as to be in mesh 20 therewith, an undercut block on that rack bar having its teeth terminating short of said gear, and a beveled block on the opposing face of the other rack bar which has a beveled end, the beveled block on said last men- 25 tioned rack bar when moved in one direction, engaging the undercut block in the first mentioned rack bar to cause its teeth to engage the gear, the beveled end of said rack bar when moved in the other direction, being 30 adapted to engage said undercut block when said end approaches the gear.

8. In a construction of the kind described, the combination of two ventilator sections, including panels, means providing a piv- 35 otal connection for the adjacent spaced apart margins of said ventilator sections, means for swinging said sections into an opening and closed position, a ridge piece closing the space between said sections, said ridge piece 40 having longitudinal grooves in its sides into which the margins of said section panels extend, said grooves being so constructed and so arranged with reference to said pivotal connection of said sections that said ridge 45 piece will rise and fall to accommodate the arcuate movement of said panel margins as

said sections move into open and closed positions.

9. A ridge ventilator construction of the kind described, comprising in combination 50 with means providing a ventilation opening, oppositely arranged angularly disposed ventilator sections normally closing said opening, said ventilator sections being pivoted at their adjacent margins and being capable 55 of a swinging movement away from and toward said ventilator opening, adjacent rack bars, one operatively connected with each section near its outer margin, and a gear pinion associated with both rack bars, said 60 rack bars and gear being so arranged and so positioned with respect to each other that when the gear pinion is rotated in one direction, one rack bar is operatively engaged therewith and the other rack bar is disengaged therefrom and when said gear pinion is rotated in the other direction, the second 65 rack bar is operatively engaged therewith and the first one is disengaged therefrom.

10. In a construction of the kind described, 70 the combination of two ventilator sections, including panels, means providing a pivotal connection for the adjacent spaced apart margins of said ventilator sections, means for swinging said sections into an open and 75 closed position, a ridge piece closing the space between said sections, the marginal parts of said ridge piece engaging the marginal parts of the ventilator sections in a manner permitting the ridge piece to rise 80 and fall to accommodate the arcuate movement of said marginal parts of said sections as said sections move into open and closed positions.

In testimony that I claim the foregoing as 85 my invention, I affix my signature in the presence of two witnesses, this 11th day of December, A. D. 1920.

JOSEPH SYLVAN.
